US0D1008371S

(12) **United States Design Patent** (10) Patent No.: **US D1,008,371 S**
 Rajopadhye et al. (45) Date of Patent: ** Dec. 19, 2023

(54) **HARVESTER VEHICLE, TOY AND/OR REPLICA THEREOF**

(71) Applicant: **Deere & Company**, Moline, IL (US)

(72) Inventors: **Dhananjay Rajopadhye**, Pune (IN); **Paul M. Richardel**, Polk City, IA (US); **Paul J. McCredie**, Bettendorf, IA (US); **Shantanu Acharya**, Pune (IN); **Vivek Vedpathak**, Pune (IN); **Omkar Thurumalla**, Mississauga (CA); **Felix Nagelin**, Malibu, CA (US); **Tobias Adami**, Munich (DE)

(73) Assignee: **DEERE & COMPANY**, Moline, IL (US)

(**) Term: **15 Years**

(21) Appl. No.: **29/873,593**

(22) Filed: **Apr. 4, 2023**

(57) **CLAIM**

The ornamental design for a harvester vehicle, toy and/or replica thereof, as shown and described.

DESCRIPTION

FIG. 1 is a perspective view of a harvester vehicle, toy and/or replica thereof according to our new design;

FIG. 2 is a first end elevational view thereof;

FIG. 3 is a second end elevational view thereof;

FIG. 4 is a first side elevational view thereof;

FIG. 5 is a second side elevational view thereof;

FIG. 6 is a top plan view thereof; and,

FIG. 7 is a bottom plan view thereof.

The dashed lines depict environment subject matter that forms no part of the claimed design.

1 Claim, 7 Drawing Sheets
